UNITED STATES PATENT OFFICE.

SVEN GUNNAR BROGREN AND KALEB KARLSSON, OF GOTTFENBORG, SWEDEN.

BURNER FOR PETROLEUM STOVES.

1,406,338.

Specification of Letters Patent. Patented Feb. 14, 1922.

Application filed April 22, 1921. Serial No. 463,718.

To all whom it may concern:

Be it known that we, SVEN GUNNAR BROGREN and KALEB KARLSSON, subjects of the King of Sweden, residing at Gottenborg, in the Province of Gottenborg and Bohus, Sweden, have invented certain new and useful Improvements in Burners for Petroleum Stoves, of which the following is a specification.

10 This invention refers to vaporizing burners for paraffin stoves, and has for its object to provide a vaporizing burner which can be easily cleaned if clogged by grit or other deposits or impurities in the oil.

15 Vaporizing paraffin burners hitherto known suffer generally from the difficulty of an effective cleaning of the rather narrow channels for the flow of the not yet vaporized liquid fuel as well as the already vaporized or gaseous fuel when clogged by the deposits in the fuel. This objection mainly depends upon the design of the burners since the supply pipes for the liquid fuel to the vaporizer as well as the ducts from the vaporizer to the nozzle of the burner generally are drawn in some curved bends so as to not permit a thorough pickering of the channels.

20 Also said ducts generally are attached to each other as well as to the vaporizer by means of soldering, thus making it necessary to dismount the entire device by the aid of a skilled workman before the cleaning can be performed and when this procedure has been completed, once again solder the

25 parts together. These time wasting and somewhat costly operations often make it more convenient to remove the clogged sample and replace it by an entirely new burner.

30 The object of this invention is to overcome the said inconveniences and to provide a burner which can be easily cleaned by any one even if not a skilled mechanician so that the same burner can be retained and used for a long period.

35 In the accompanying drawing an embodiment of the invention is illustrated, wherein Figures 1 and 2 show two various side elevations of the improved burner with certain parts removed, and Figure 3 a plan view of

40 the burner.

In the drawing 1 denotes the supply pipe of the liquid fuel, the said pipe having mainly a vertically rectilinear shape and is provided at its upper end with threads 2, by means of which the pipe is attached to

45 the vaporizer 3 and at its lower end with

threads 4 for attaching the burner to the fuel tank, whereby the pipe 1 also forms a support for the burner proper. The vaporizer 3 is disposed within a portion 6 of a washer or ring 5 serving as a distributor of the flame. The vaporizer 3 by means of a channel 7 passing circumferentially in relation to the ring 5 communicates with a channel 8 disposed in the axial plane of the ring 5 and forming angle to the axial centre line of the ring 5. The channel 8 is at its lower end provided with threads and joined to the substantially straight-lined gas pipe 10 to the outlet nozzle 11, for which purpose the pipe 10 in the upper end is provided with threads 12. The inclination of the channel 8 and of the pipe 10 is chosen such, that the nozzle 11, which is screwed in a compartment 13 fastened to the lower end of the pipe 10, will be situated below the centre of the opening of the ring 5.

When the gas pipe 10 ought to be cleaned from deposits the said pipe is unscrewed, which eventually can necessitate a preceding unscrewing of the pipe 1, if the two pipes are disposed so close together as shown in the drawing, wherein the channel 7 is comparatively short. If this channel 7, however, should be so long, that the pipes 1 and 10 for instance can be disposed on diametrically opposite sides of the ring 5, such a previous removing of the pipe 1 will not be necessary, in which case the pipe 1 may be attached to the portion 6 also by soldering if proved more convenient.

In order to enable an occasional cleaning of the gas pipe 10 without need to unscrew it, a removable mud plug 14 can be fitted in the upper end of the channel 8, so that by unscrewing said plug 14 a pricker can be inserted into the pipe 10 and remove any grit or other deposits in the bottom of the channel 8.

45 In connection with the foregoing attention is directed to the relation of the seat 13 with respect to the pipe 1 the latter forming a support so that when the nozzle is being attached or disconnected it receives strains on the pipe 10 and prevents loosening of this pipe at the joint of the vaporizer.

50 It must be understood, that the invention is not limited to the special design of the burner here described and shown in the drawing but the details of the apparatus may be varied in several respects in shape and design within the scope of the invention.

What is claimed as new and wanted to protect by Letters Patent is:—

1. In a vaporizing paraffin burner an annular flame distributor, a vaporizer provided 5 non symmetrically at the one side of said annular flame distributor a substantially rectilinear gas duct going obliquely in relation to the axial centre line of said annular flame distributor from said vaporizer to a burner nozzle disposed in the axial centre line of said annular flame distributor.
2. In a vaporizing paraffin burner, in combination, an annular flame distributor, a vaporizer provided non-symmetrically at one 15 side of said annular distributor, a substantially rectilinear gas duct leading from said vaporizer, a burner nozzle disposed in the center line of the flame distributor and connected with the gas duct, a substantially rectilinear supply pipe for liquid fuel to said vaporizer, said supply pipe sloping downwardly in relation to the center line of the 20

annular flame distributor and terminating in a screw-threaded end portion disposed coaxially with the center line of said annular 25 flame distributor.

3. In a vaporizing paraffin burner, in combination, an annular flame distributor, a vaporizer provided non-symmetrically at one side of said annular distributor, a supply 30 pipe for liquid fuel leading to said vaporizer, a gas duct in communication with the vaporizer and arranged in a sloping position in relation to the center line of said flame distributor, a seat at the terminal of the gas 35 duct, a screw-threaded burner nozzle detachably engaged in the seat and said seat being disposed close to said fuel supply pipe so as to be supported thereby, as and for the purpose set forth.

In testimony whereof we have affixed our signatures.

SVEN GUNNAR BROGREN.
KALEB KARLSSON.
